[57] CLAIM

The ornamental design for an air pre-cooler unit for air conditioners or the like, as shown and described.

DESCRIPTION

FIG. 1 is a perspective view taken from the top, rear and left side of an air pre-cooler unit for air conditioners or the like showing our new design;

FIG. 2 is a perspective view taken from the bottom, front and right side thereof; and

FIG. 3 is a top plan view thereof.
